EDUARD NOTTEBOHM, OF MANILA, PHILIPPINE ISLANDS.

ROOFING-TILE.

1,237,687.

Specification of Letters Patent. Patented Aug. 21, 1917.

Application filed August 16, 1916. Serial No. 115,175.

To all whom it may concern:

Be it known that I, EDUARD NOTTEBOHM, a citizen of Germany, residing at Manila, in the Province of Manila, Philippine Islands, have invented new and useful Improvements 5 in Roofing-Tiles, of which the following is a specification.

My invention relates to improvements in roofing tiles and is especially designed to 10 form such an interlock of the tiles when laid, as to prevent leakage between the tiles, which may occur during violent storms of wind and rain.

It consists of transverse rims so arranged 15 as to prevent the water from being forced under the tiles, and insures its passing through the extreme end. It also comprises longitudinally disposed grooves forming double interlocking channels of such depth 20 as to prevent the water from over-running these channels transversely, while the channels themselves will form a method of egress for such water as may possibly be forced into them.

25 Referring to the accompanying drawings for a more complete explanation of my invention,

Figure 1 is a perspective view of a tile.

Fig. 2 is a top view.

30 Fig. 3 is a bottom view.

Fig. 4 is a transverse section on line 4—4 of Fig. 5.

Fig. 5 is a vertical section through the roof in line 5—5 of Fig. 4.

35 Fig. 6 is a sectional view of a flat tile fragment.

The object of my invention is to provide an interlocking tile of such a character that the tiles will be held in proper relative position 40 when laid and the grooves or channels are so placed with relation to the water conducting channel that they will prevent any leakage caused by the most violent storms.

As shown in the drawings, A is a tile made 45 in an S-form, one edge of which is upturned and the other edge is correspondingly turned downwardly. The upturned edge of the tile has grooves or channels 2^a, extending lengthwise of the tile and the opposite or lower edge is formed with corresponding tongues 3, which are adapted to

fit into the grooves or channels of the next succeeding tile, when laid. These tiles may be made of any suitable material. They may be made of iron, or burnt clay, or cement and sand, or other material.

Transversely across the head of each tile is a raised rib 4, which unites with the longitudinal rib 5 forming the extreme upper longitudinal edge of the tile, and the side of 60 the channel 2; 6 is a second raised transverse rib, which unites with the inner longitudinal rib 7, which forms the inner side of the groove or channel 2^a. Transversely across the upper end of the lower surface of 65 each tile is a lug 11 which may engage and form a stop against a purlin, and transversely across the bottom of each tile near the lower end, are lugs 12 and 13, with a groove between which, when the tile is laid, 70 will engage and interlock with the legs 4 and 6 at the top.

The lower curve of the S-shaped tile is flattened as shown at 8 and rests upon a supporting purlin 9, and 10 is a lug contiguous to the purlin, having a hole made in it, through which a wire may pass and be twisted around the purlin to prevent the tiles being lifted in case of a furious storm. Tiles formed in this manner will lie so closely and 80 be so interlocked, that it will be impossible for storms of wind and rain to penetrate the joints between the tiles and a very lasting, durable roof covering is thus provided.

Having thus described my invention what 85 I claim and desire to secure by Letters Patent is—

An S-shaped tile having an interlocking upturned edge, said interlock consisting of a rib extending lengthwise on the edge adjacent the outer surface of the tile and above the level of the water conducting channel, a second and higher rib disposed inwardly and separated from the first rib by a groove, and a third rib disposed inwardly from and 90 above the second rib and separated from the latter by a second groove arranged above the first groove, and an interlocking downturned edge having ribs and grooves to interlock with the grooves and ribs respectively of an upturned edge of an adjacent block, said downturned edge having a flat 100

face seating on the first shoulder above the bottom of the water conducting channel whereby the outer surfaces of adjacent tiles will lie flush with each other to uninterrupt 5 the continuous curved outlines of contiguous tiles.

In testimony whereof I have hereunto set

my hand in the presence of subscribing witnesses.

EDUARD NOTTEBOHM.

Witnesses:

WALTHER Mox,

EMIL MEYER,

MIGUEL HENRY.
